ABSTRACT OF THE DISCLOSURE

A gas-filled electric discharge device having an apertured control electrode and a correspondingly apertured electrode between the control electrode and the anode which serves to prevent deterioration of the performance of the device under hold-off conditions due to erosion of the anode.

This invention relates to gas-filled electric discharge devices.

The invention relates particularly to gas-filled electric discharge devices of the kind including an electrode structure including an anode, a cathode and a control electrode, disposed between the anode and the cathode, in which is provided at least one elongated aperture through which the discharge between the anode and the cathode passes in operation.

In this specification the term gas-filled is intended to include vapour-filled.

In use of electric discharge devices of the kind specified the anode may be subject to erosion due to high energy particles being swept into collision with the anode. This phenomenon may occur in a thyratron, for example, during the short period which elapses between the commencement of the discharge and the collapse of the anode to cathode voltage, during which period electrons from the region of the discharge may be accelerated towards the anode. In a vapour-filled device employed as a rectifier, such erosion may occur due to positive ions being accelerated towards the anode during the non-conducting half cycle of the device, when the anode may be at a high negative potential with respect to the cathode.

Whatever the cause, the resulting erosion produces irregularities in the shape of the surface of the anode, and hence in the configuration of the electric field between the anode and the cathode, and this may lead to a deterioration in the performance of the device when the device is non-conducting.

It is an object of the present invention to provide an electric discharge device of the kind specified wherein this difficulty is alleviated.

According to the present invention, in an electric discharge device of the kind specified there is disposed between the anode and said control electrode an additional electrode which is electrically insulated from said control electrode and in which, for each said aperture in the control electrode, there is a corresponding aperture which is of substantially the same size and shape as the corresponding aperture in the control electrode, and which, in respect of the path of a discharge between the anode and the control electrode, is at least approximately in register with the corresponding aperture in the control electrode.

It will be appreciated that said anode may constitute the main anode of the device, that is the anode carrying the lead current of the device, or may constitute an auxiliary anode of the device, for example, an electrode whose purpose is to increase the hold-off voltage of the device.

2

One arrangement in accordance with the invention will now be described, by way of example, with reference to the accompanying drawings in which:

FIGURE 1 is a sectional elevation of a thyratron having a forward hold-off voltage of 35 kilovolts and adapted to pass a peak current of 5000 amps, and

FIGURE 2 is a plan view of an electrode of the thyratron.

The thyratron has a sealed envelope filled with deuterium at a pressure of 0.25 torr.

Referring to the drawing, the main body of the envelope is in the form of a hollow, generally cylindrical structure incorporating two tubular metal members 1 and 2 of lengths 4.5 inches and 1.5 inches respectively and each having an internal diameter of 3.75 inches, apart from slight variations in diameter for the purpose of providing locating shoulders at various positions. The two tubular members 1 and 2 are disposed in axial alignment and communicate via a relatively short, narrow, tubular ceramic section 3 of the envelope. At one end, the ceramic section 3 is joined to the shorter tubular metal member 2 by means of a thin-walled tubular metal sealing ring 4 which at one end is sealed to the inner edge of a flange 5 extending inwardly from the adjacent end of the tubular member 2, and at its other end is provided with an outwardly extending flange 6 which is sandwiched between the adjacent end of the ceramic section 3 and a ceramic backing ring 7. At its other end the ceramic section 3 is joined to the longer tubular metal member 1 by means of a thin-walled tubular metal sealing ring 8 having an inwardly extending flange 9 at one end and an outwardly extending flange 10 at the other end, the inwardly extending flange 9 being sandwiched between the adjacent end of the ceramic section 3 and a ceramic backing ring 11 and the outwardly extending flange 10 being sealed to the face of an inwardly extending flange 12 provided at the adjacent end of the tubular member 1.

To shield the inner surfaces of the ceramic section 3 and the backing ring 11 from the discharge in operation, a short tubular metal member 13 is disposed coaxially within the ceramic section 3, this member 13 being joined at one end to the inner edge of the flange 12.

At its end remote from the ceramic section 3 of the envelope, the longer tubular member 1 is sealed to an annular cup-shaped metal sealing ring 14 which nests within and is sealed to a second annular cup-shaped metal sealing ring 15. The sealing ring 15 is sealed in turn to one end of a ceramic ring 16 with the aid of a backing ring 17, and the other end of the ceramic ring 16 is sealed to one main face of an outwardly extending flange 18 formed around the mouth of a cup-shaped metal member 19 whose base extends across the end of the main body of the envelope. The other main face of the flange 18 is sealed to one end of a further ceramic ring 20 whose other end is sealed with the aid of a backing ring 21 to a compartment 22 which serves to close this end of the envelope and which houses a replenisher for the gas filling of the thyratron. The replenisher communicates with the interior of the main body of the envelope via four apertures 23 in the end of the replenisher compartment 22 and an aperture 24 formed through the base of the member 19.

At the end of the shorter tubular member 2 remote from the ceramic section 3 of the envelope there is provided an inwardly extending flange 25 to which a tubular ceramic member 26 is joined by means of a thin-walled tubular metal sealing ring 27. The sealing ring 27 is provided at one end with an outwardly extending flange 28 which is sealed to the flange 25, and at its other end is provided with an inwardly extending flange 29 which is sandwiched between the end of the ceramic member

26 and a ceramic backing ring 30. The ceramic member 26 has an internal diameter of 2.38 inches and a length of 3.0 inches. Within the ceramic member 26 there is housed coaxially a thin-walled tubular metal member 31. The inner end of the tubular member 31 lies just within the compartment formed by the tubular member 2 and the flanges 5 and 25, and at its outer end the tubular member 31 is provided with an outwardly extending flange 32 which is sealed between the end of the ceramic member 26 and a relatively short tubular ceramic member 33. Half way along its length, the tubular member 31 is provided with a number of outwardly projecting pips 34 which serve to locate the member 31 within the ceramic member 26.

A further thin-walled tubular metal member 35 is disposed coaxially within the tubular member 31, the inner end of the member 35 lying in a plane positioned about one third of the way along the length of the tubular member 31 in the direction towards the main body of the envelope. At its outer end the tubular member is provided with an outwardly extending flange 36 which is sealed between the end of the ceramic member 33 and a backing ring 37.

The electrode system of the thyratron is housed within the main body of the envelope and comprises an anode 38, a control electrode 39, a baffle 40, a cathode 41, and an additional electrode 42, hereinafter referred to as the dummy anode.

The anode 38 is in the form of a disc of molybdenum which is housed just within the inner end of the tubular member 31 and is supported at one end of a metal tube 52. The tube 52 extends away from the anode 38 coaxially through the tubular member 31 to a plane about one third of the way along the length of the tubular member 35, the tube 52 being sealed coaxially within the tubular member 35 where these two members 35 and 43 overlap, thereby closing this end of the envelope.

The dummy anode is in the form of a thin copper disc secured to the inner end of the tubular member 31 so as to be disposed parallel to the anode 38 at a distance of 0.16 inch from the anode 38. In the centre of the dummy anode 42 there is formed a cross-shaped aperture 43, each of the four limbs of the aperture 43 having a width of 0.08 inch and a length of 0.89 inch.

Referring now to FIGURES 1 and 2, the control electrode 39 comprises a copper disc of thickness 0.15 inch which is sealed into the tubular envelope member 2 so as to be disposed parallel to the dummy anode 42 at a distance of 0.16 inch from the dummy anode 42. The face of the control electrode 39 remote from the dummy anode 42 is recessed to provide a central circular area 44 of diameter 2.0 inches and thickness 0.08 inch. In the area 44 there is formed centrally a cross-shaped aperture 45 which is of the same dimensions and is in register with the aperture 43 in the dummy anode 42.

The baffle 40 comprises a molybdenum disc of thickness 0.08 inch and diameter 2.25 inches disposed within the longer tubular member 1 in a plane perpendicular to the axis of the envelope. The baffle 40 is mounted, by means of a copper support 46 on and in good electric and thermal contact with the flange 12 on the tubular member 1 at a distance of 0.375 inch from the flange 12.

The cathode 41 is also housed within the tubular member 1 and is of the type described in the specification of my Patent No. 3,244,925. The cathode 41 essentially comprises a hollow cylindrical member 47 made of electron emitting material in which is housed an electric heater 48. The cathode 41 is supported coaxially within a metal heat shield 49 which is generally tubular in shape and at its end remote from the anode 38 is mounted on the cup-shaped metal member 19.

The heat shield 49 is provided with a series of spaced rectangular fins 50 which project radially inwards, the fins 50 being approximately the same length as the cathode 41. The internal surface of the heat shield 49

and the surfaces of the fins 50 are coated with electron emissive material derived from the cathode 41, deposition of this material being effected during manufacture of the thyratron.

Connection to the control electrode 39 is made via the tubular member 2, connection to the cathode 41 and one end of the cathode heater 48 is made via the metal member 19, connection to the other end of the cathode heater 48 is made via a metal part of the envelope of the replenisher compartment 22 and connection to an electrical heating element (not shown) included in the replenisher is also made in this way. Connection to the anode 38 is made via a threaded metal boss 51, and connection to the dummy anode is made via the tubular member 31.

In operation of the thyratron, a voltage of the order of 35 kilovolts is applied between the anode 38 and the cathode 41, the anode 38 being positive with respect to the cathode 41, and the dummy anode 42 is connected to the anode 38 via a resistor (not shown) of high value. To hold the thyratron in a non-conducting condition the control electrode 39 is maintained at substantially the same potential as the cathode 41, and the thyratron is fired by the application of a positive voltage pulse to the control electrode 39, the resulting discharge passing through the apertures 45 and 43 in the control electrode 39 and the dummy anode 42.

It will be appreciated that the presence of the high valued resistor between the anode 38 and the dummy anode 42 ensures that the discharge passes to the anode 38 and not to the dummy anode 42.

When the thyratron is non-conducting, the dummy anode 42 is substantially at the anode potential and the width of the aperture 43 in the dummy anode 42 is sufficiently small for the configuration of the electric field on the cathode side of the dummy anode to be unaffected by the shape of the surface of the anode 38. Thus, by virtue of the presence of the dummy anode 42, deterioration of the performance of the thyratron under hold-off conditions due to erosion of the anode 38 by high energy particles after a period of operation is to a large extent prevented whilst the performance of the thyratron when conducting is substantially unaffected by the presence of the dummy anode 42. The dummy anode 42 is not itself subject to erosion to any appreciable extent because the vast majority of the high energy particles causing erosion will pass through the aperture 43 in the dummy anode 42 and will therefore not impinge on the surface of the dummy anode 42.

I claim:

1. An electric discharge device having a sealed envelope; a gas-filling within the envelope, and an electrode structure within the envelope, said structure comprising: an anode, a cathode, a control electrode, disposed between the cathode and the anode, in which control electrode is formed at least one elongated aperture through which the discharge between the anode and the cathode passes in operation, and an additional electrode which is disposed between the anode and the control electrode, which additional electrode is electrically insulated from the control electrode and in which, for each said aperture in the control electrode, there is a corresponding aperture which is substantially the same shape as the corresponding aperture in the control electrode and is at least approximately in register with the corresponding aperture in the control electrode with respect to the path of the discharge between the anode and the control electrode, the width of each said aperture in the additional electrode being sufficiently small substantially to prevent penetration of that aperture by electric field lines when the device is non-conducting so that the configuration of the electric field on the cathode side of the additional electrode is unaffected by the shape of the surface of the anode.

2. A device according to claim 1 wherein said additional electrode is electrically insulated from all the other electrodes of the device.

3. A device according to claim 1 wherein said additional electrode comprises an apertured planar metal member.

4. A device according to claim 1 wherein there is only one said aperture in the control electrode.

5. A device according to claim 4 wherein said aperture in the control electrode is cross-shaped.

6. An arrangement for operating an electric discharge device according to claim 1 including a resistive connection between the anode and said additional electrode so that when the discharge device is not conducting said additional electrode is at substantially the same potential as the anode, but when the discharge device is conducting

5
the discharge passes to the anode rather than the additional electrode.
